UNITED STATES PATENT OFFICE.

JAMES ALLEN HUGGINS, OF RED SPRINGS, NORTH CAROLINA.

PLOW.

1,033,323.

Specification of Letters Patent. Patented July 23, 1912.

Application filed June 27, 1911. Serial No. 635,561.

To all whom it may concern:

Be it known that I, JAMES ALLEN HUGGINS, a citizen of the United States, residing at Red Springs, in the county of Robeson 5 and State of North Carolina, have invented certain new and useful Improvements in Plows; and I do declare the following to be a full, clear, and exact description of the invention, such as will enable others 10 skilled in the art to which it appertains to make and use the same.

This invention relates to improvements in plows.

One object of the invention is to provide 15 a plow having a pivoted standard adapted to be adjusted to regulate the position of the blade or shovel of the plow and having a runner bar adapted to be automatically adjusted by the movement of the beam to correspond with the adjusted position of the 20 blade or shovel.

Another object is to provide a runner and blade adjusting mechanism for plows which will be simple, strong and durable in 25 construction, efficient in operation and well adapted to the purpose for which it is designed.

With these and other objects in view the 30 invention consists of certain novel features of construction, combination and arrangement of parts as will be more fully described and claimed.

In the accompanying drawings: Figure 1 is a side view of a portion of a plow embodying the invention, parts being broken away; Fig. 2 is a similar view showing the parts adjusted to another position; Fig. 3 is a cross sectional view on the line 3—3 of Fig. 1; Fig. 4 is a horizontal sectional view 40 on the line 4—4 of Fig. 1; Fig. 5 is a view similar to Fig. 1 showing a modified form of the invention; Fig. 6 is a similar view showing the parts adjusted to another position; Fig. 7 is a cross sectional view on the 45 line 7—7 of Fig. 5. Fig. 8 is a side view partly in section showing the application of the invention to a wooden beam plow.

Referring more particularly to Figs. 1, 2 and 3 of the drawings, 1 denotes the plow 50 beam which is provided near its rear end with a longitudinal slot 1^a. The beam 1 has a segmental downwardly curved rear portion 2 to the lower end of which is pivotally connected the rear ends of a pair of runner 55 supporting and standard attaching bars 3.

To the forward ends of the bars 3 is connected the lower end of the adjustable standard 4 of the plow. The lower portion of the standard 4 is bifurcated and the upper portion projects through the slot in the beam 1 and forms a lever 5 whereby the standard is swung backward and forward on its pivotal connection with the bars 3 thereby tilting the plow blade or shovel 6 to the desired angle. The upper or lever 65 portion 5 of the standard is provided with a spring projected pawl 7 adapted to work through the slot 1^a and to be engaged with a segmental rack bar 8 secured to and spaced a suitable distance below the beam as shown. 70 In the standard and adapted to slidably engage the space between the rack bar 8 and the lower edge of the beam is a guide pin 9. Pivots connected to the bars 3 are pairs of runner adjusting levers 10 and 11. The 75 lower ends of the levers 10 and 11 are curved and have formed therein curved slots 12 as shown. To the curved lower ends of the levers 10 and 11 is connected a runner 13 having a central upwardly extending web 80 13^a which is disposed between the lower ends of the levers 10 and 11 and has arranged therein transversely disposed pins 14 which are engaged with the slots 12 whereby when the levers are rocked in the proper direction the runner will be raised and lowered. 85

The pairs of levers 10 and 11 are connected together to operate in unison by a link or connecting bar 15. The levers 10 are 90 considerably longer than the levers 11 and said levers 10 are connected at their upper ends to the standard 4 by a link 16 whereby when the standard is swung forwardly or rearwardly to adjust the blade or shovel of the plow the levers 10 and 11 will be simultaneously rocked through the links 15 and 16 thus raising and lowering the runner 13 whereby the relative position thereof with respect to the blade or shovel is maintained. 100 When thus operated the runner will be raised and lowered straight or directly up and down.

In Figs. 5, 6 and 7 of the drawings is shown a slightly modified form of the invention. In this form of the invention the beam 17 has a rear downwardly curved portion similar to that shown in the first figures of the drawings. To the lower end of said downwardly curved rear portion of the 110

beam are pivotally connected the rear ends of a pair of forwardly extending parallel runner supporting and standard attaching bars 18 to the forward ends of which is pivotally connected the bifurcated lower portion 5 of a standard 19 on the lower end of which is secured the blade or shovel 20 of the plow. The upper end of the standard projects above the beam and forms a lever 21 whereby the standard is operated. The upper or lever portion 21 of the standard is provided with a spring projected pawl 22 which is adapted to engage a segmental rack 23 secured to the upper edge of the downwardly curved rear end of the beam as shown. By means of the pawl 22 and rack 23 the lever and standard of the plow are secured in their adjusted positions. Arranged through the standard 19 adjacent to the lower edge of the beam is a transversely disposed guide pin 24 which assists in guiding and holding the standard in position. Pivotally connected to the bars 18 and arranged between the same are pairs of land side attaching bars 25 and 26 to the lower ends of which is pivotally connected a runner 27 having a central upwardly extending web 28 in the upper edge of which are formed notches 29 the purpose of which will be hereinafter described. The levers 25 are of considerably greater length than the levers 26 and said levers 25 are pivotally connected at their upper ends to the standards 19 by a link 30. The levers 25 are connected at their upper ends to the levers 26 by a link 31 whereby said levers are caused to operate in unison when actuated by the standard. By thus connecting the runner 27 to the levers 25 and 26, said runner will be 40 lifted by a forward circular movement when the standard is rocked to adjust the blades of the plow thus simultaneously and automatically adjusting the runner whereby the latter is caused to maintain the same relative 45 position with respect to the plow blade or shovel. When the runner is lifted in the manner described the notches 29 in the web 28 thereof engage the pivot bolts by which the pairs of levers 25 and 26 are connected 50 to the attaching bars 18.

In Fig. 8 of the drawings the invention is shown as being applied to a plow having a wooden beam 32 to the rear end of which are connected the upper ends of substantially right angular standard attaching bars 33 said upper ends of the bars being provided with series of bolt holes 34 adapted to receive a fastening bolt 35 whereby the end of the beam may be adjustably connected to 60 the attaching bars. To the forward ends of the lower portion of the attaching bars 33 is pivotally connected the lower end of a bifurcated standard 36 the upper end of which projects through a slot 37 formed in 65 the beam 32 and has connected thereto an

operating lever 38 whereby said standard may be adjusted to regulate the position of the plow blade or shovel 39 secured to the lower end thereof as shown. The lever is provided with a spring projected pawl 40 which is adapted to be engaged with the teeth of a curved rack bar 41 secured at its upper end to the beam 32 and at its lower end to the upwardly extending rear portions of the attaching bars 33 as shown. The bifurcated standard 36 is adapted to straddle the rack bar 41 and through the standard adjacent to the lower edge of said rack bar is arranged a guide pin 42. Pivotally connected to the lower horizontal portions of the attaching bars 33 are pairs of runner supporting levers 43 and 44 to the lower ends of which is pivotally connected a runner 45. The levers 43 are connected at their upper ends to the standard 36 by a link 46 and said pairs of levers 43 and 44 are connected together by a link 47 whereby said levers are moved in unison by the standard 36 and lever 38 thus raising and lowering the runner 45 to cause the same to maintain the same relative position with respect to the shovel or blade 39 of the plow when the latter is tilted. The runner 45 is constructed in the same manner as those described in the previous forms of the invention and in its web are formed notches 48 which engage the pivot pins of the pairs of levers 43 and 44 when said runner is raised by said lever. By constructing and arranging the curved rack bar 41 as herein shown and described said bar also forms a brace for the beam of the plow, said beam being pivotally connected to the upper end of the bar to permit the rear end of the beam to be adjustably connected to the upper ends of the attaching bars 33 as hereinbefore described.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention claimed.

Having thus described my invention, what I claim is:

1. In a plow, a blade, swinging blade-supporting mechanism, a runner, and connections between the latter and said mechanism whereby the runner is held ever in a horizontal plane and automatically adjusted vertically when the angle of the blade to a horizontal is changed.
2. In a plow, a blade, adjustable blade-supporting mechanism, a runner, levers having arms of equal length supporting the ends of said runners, and connections between the levers and said mechanism where-

by the runner is automatically adjusted vertically when the position of the blade is changed.

3. In a plow, bars rigidly carried by the beam, blade-supporting mechanism pivoted to said bars and adjustably connected with the beam, a runner, and connections between the latter and said mechanism whereby the runner is automatically adjusted when the 10 position of the blade is changed.

4. In a plow, bars carried by the beam, blade-supporting mechanism pivoted to said bars and adjustably connected with the beam, a runner, levers adjustably connecting the latter with said bars, and connections between the levers and said mechanism whereby the runner is automatically adjusted when the position of the blade is changed.

20 5. In a plow, bars carried by the beam, blade-supporting mechanism pivoted to the bars and adjustably connected with the beam, a runner, levers adjustably connecting the latter with said bars, a link connecting the levers, and another link connecting one lever with said blade-supporting mechanism whereby the runner is automatically adjusted when the position of the blade is changed.

6. In a plow, parallel bars carried by the beam, blade-supporting mechanism pivoted to said bars and adjustably connected with the beam, a runner having an upwardly projecting web with notches in its upper edge, levers between and pivotally connected 35 with said bars and with said web, and connections between the levers and said blade-supporting mechanism whereby the movements of the latter to adjust the position of the blade will automatically adjust the runner and the notches in its web will engage the pivots between said levers and bars when the web is raised.

7. In a plow, a beam, runner supporting bars secured at one end to the rear end of 45 said beam, a blade supporting standard connected to the other ends of said bars, a blade carried by said standard, means whereby said standard is adjustably secured to the beam of the plow, runner supporting levers 50 pivotally connected to said bars, one of said levers extending upwardly above the other lever, a link to connect the upper end of said extended lever to said standard, a connecting bar to connect said levers together 55 whereby the same are adapted to move in unison, a runner pivotally connected to the lower ends of said levers whereby when

said standard is adjusted the movement thereof will be imparted through said levers to said runner and the latter will be adjusted to maintain the same relative position between the plow blade and runner.

8. In a plow, a beam, runner supporting bars secured at one end to the rear end of the beam, a blade supporting standard pivotally connected to the forward ends of the supporting bars, a blade secured to the lower end of said standard, a lever arranged on the upper end of said standard, a locking pawl carried by said lever, a segmental rack 70 secured to the beam and adapted to receive said pawl whereby the standard and lever are locked in their adjusted positions, a runner adjustably connected to said supporting bars, and means to connect said 75 runner with the standard of the plow whereby said runner is automatically adjusted vertically by the standard when the latter is adjusted around its pivot, thereby maintaining said runner in a constant horizontal 80 position.

9. In a plow, a beam, runner supporting bars having substantially right angular upwardly projecting rear ends, means to adjustably connect the rear end of the beam 85 with said upper ends of the supporting bars, a blade supporting standard pivotally connected at its lower end to the forward ends of the lower portions of said supporting bars, a blade carried by said standard, a 90 combined rack and beam-bracing bar secured at its lower end to said supporting bars and at its upper end to the beam, a lever arranged on the upper end of said standard, a spring-projected pawl carried by said 95 lever and adapted to engage the teeth of said combined rack bar and brace whereby the standard is held in its adjusted positions, a runner adjustably secured to said supporting bars, and means to connect said 100 runner with the standard of the plow whereby the runner is automatically adjusted by the standard when the latter is actuated to adjust the blade thereby maintaining said runner and blade in proper relative position.

In testimony whereof I have hereunto set my hand in presence of two subscribing witnesses.

JAMES ALLEN HUGGINS.
